UNITED STATES PATENT OFFICE

1,982,687

PILE

James J. O'Brien, Wayne, Pa.

Application May 29, 1931, Serial No. 540,847

4 Claims. (Cl. 61—53)

The main object of the invention is to provide a supporting foundation structure, or pile, whose bearing strength and frictional resistive strength may be materially increased after the structure 5 has penetrated to a predetermined or maximum depth. This object is accomplished by providing means, such as projections or prongs, operable from the head of the pile, which effect a lateral or radial penetration of the soil surrounding the 10 main pile body. The prongs are preferably so arranged and operated that they offer little or no resistance to the driving of the pile and do not ordinarily function as specified until after the pile is driven. However, they are operable, at the 15 will of the operator, at any stage of the pile driving operation. The prongs may be of any number, size or shape, and may be arranged at different levels along the pile and may extend, when in ultimate functioning position, in different radial directions from the axis of the pile; so that 20 the controlling factor in the amount of load that can be carried by the pile approaches the strength of the materials of which the pile is constructed.

Approximately full strength of the pile may 25 be obtained with a materially decreased driving force due to the small percentage of total area of the pile exposed to soil resistance against driving to desired possible penetration, which has the effect of exerting the required force per square 30 inch to overcome soil resistance to driving, with a materially decreased total driving force.

A total strength of pile equal to that of any other pile heretofore used may be obtained with much less penetration.

35 By spreading the bearing area and frictional resistance area by the means specified, the arch action of soil resistance may be utilized and advantage may be taken of the possibly strong resistive strata through which the pile may extend, 40 any voids that may exist being closed by grouting or pressure grouting with cement mortar or cement concrete.

In the drawing, which shows one embodiment of the invention, and a modification thereof:

45 Fig. 1 is a vertical section through the middle of the pile before the inner mandrel is driven home relative to the shell.

Fig. 2 is a plan view of the top of the pile.

Fig. 3 is a horizontal section on the line 3—3 50 of Fig. 1.

Fig. 4 is a vertical section, taken 90° clockwise to that of Fig. 1, through the middle of the pile after the inner mandrel is driven home.

Fig. 5 is a horizontal section on the line 5—5 55 of Fig. 4.

Fig. 6 is a vertical section of an attachment that may replace the attachment shown in Figs. 1 and 3 and that is especially adaptable for hard driving.

Fig. 7 is a bottom view of the attachment of Fig. 6.

The pile comprises an outer casing or shell 1 and an inner mandrel 2. During the driving of the pile and until just before the mandrel is driven home, the mandrel and casing may be held in fixed relation one to the other by means of the attachment shown in Figs. 1 and 3. The attachment comprises two angle plates 6, 6, two flat plates, 7, 7, two bolts and nuts 10, 10, two bolts and nuts 13, 13, and a washer 14. The mandrel 2 projects above this attachment and carries a cap 8, on which the driving is done. Until the casing is driven, by action upon the cap of the mandrel, to its desired maximum penetration, the casing and mandrel maintain the relative position shown in Fig. 1. The casing has a closed bottom 9.

Hinged to the mandrel 2 at various points along its length and on different radii of its axis (say on four radii 90° apart) are prongs 3. The prongs may be hinged by bolts and nuts 11 and pipe separators 12. The free ends of the prongs rest on guide flaps 5 inclined downward toward orifices in the wall of the casing.

During the driving of the pile and until the casing has penetrated to the desired depth, the prongs 3 are functionless and since they do not extend out beyond the casing wall, they offer no resistance to driving. When the casing has penetrated to the desired depth, the above described attachment securing the casing 1 to the mandrel 2 is removed and the mandrel 2 is driven down within the shell. During this operation the prongs 3, guided by the flaps 5, swing on their pivots and at the same time are forced out through the orifices in the casing and through the surrounding soil until, when the mandrel is driven home, they occupy the radial positions shown in Figs. 4 and 5. In this position the prongs are supported, at their hinged ends, by the braces 4, and the flaps 5 have been bent down into the horizontal position shown in Fig. 4, the flaps in this position affording an additional support for the prongs.

The pile is grouted with cement mortar or cement concrete by filling the pile with grout either just before or just after driving the mandrel home. The grout may be injected by any known process, as, for example, by the method known as pressure grouting, wherein an attachment at the end of the pile forces the grout into all cavities by

the pressure of compressed air. A combination of known methods of grouting may be employed. The length and size of the pile will determine whether cement mortar or cement concrete shall be used and also by what method to apply the grout. When the grout filler has set sufficiently, the pile is ready for its load.

Instead of using the attachment above described, and shown in Figs. 1 and 3, for securing together the mandrel and casing, the attachment shown in Figs. 6 and 7 may be used. In this attachment a key 16 rests on the top of the casing 1 and under the mandrel braces 4, 4. A sleeve 15, carrying the cap 8, is then placed over the top of the mandrel, 2, resting on the top of the casing 1, the key fitting into diametrically opposite notches in the sleeve. When this attachment is used, the driving force is transmitted direct to the outer casing. When the pile has reached its desired maximum or possible penetration the attachment is removed and the inner mandrel is driven home as hereinbefore described.

The pile is protected, when necessary, by a rust-resisting process, such as galvanizing or painting.

The above embodiments of the invention are merely illustrative. If either of the embodiments described be used, the details may be varied. Thus, for the bolts by which the prongs are hung from the mandrel 2 may be substituted rivets. In some cases it may be more expedient to jet the pile down to its desired penetration by means of a water jet conveyed through a pipe extending down through the interior of the pile and connected to an orifice in the bottom shoe which will enable the water to wash away the material under the point of the pile. The inner mandrel may then be driven home as described. This modification requires no illustration, since it requires no departure from the described construc-

tion. The invention, however, may assume forms specifically quite different from those described, to which I do not wish to be limited.

Having now fully described my invention, what I claim and desire to protect by Letters Patent is:

1. A pile comprising an outer casing, an inner mandrel, and prongs carried by the mandrel at different levels within the casing and operable, by a downward movement of the mandrel relative to the casing, to be projected laterally through the wall of the casing.

2. A pile comprising an outer casing having orifices at different levels, an inner mandrel, prongs hinged on the mandrel adjacent said openings, and guides on the casing adapted, when the mandrel is moved downward relative to the casing, to constrain the prongs pivoted to the mandrel and to swing on their axes through said orifices toward a horizontal position.

3. A pile comprising an outer casing, an inner mandrel, soil-penetrating devices pivoted on said mandrel, means for holding said casing and mandrel against relative vertical movement, and means for guiding the soil-penetrating devices outwardly through the wall of the casing upon relative movement of the mandrel and casing following release of the holding means.

4. A pile comprising an outer casing, an inner mandrel, soil-penetrating devices pivoted on said mandrel, means for holding said casing and mandrel against relative vertical movement, said holding means forming a connection between the mandrel and casing whereby driving blows to sink the casing may be applied to the mandrel, and means for guiding the soil-penetrating devices outwardly through the wall of the casing upon relative movement of the mandrel and casing following release of the holding means.
